DESIGN FOR A JEWELRY PIN

Morris Horovitz, Providence, R. I., assignor to
W. & H. Jewelry Co., Providence, R. I., a corporation of Rhode Island

Application May 19, 1945, Serial No. 119,628

Term of patent 3½ years

(Cl. D45—19)

To all whom it may concern:

Be it known that I, Morris Horovitz, a citizen of the United States, residing at Providence in the county of Providence and State of Rhode Island have invented a new, original, and ornamental Design for a Jewelry Pin, of which the following is a specification, reference being had to the accompanying drawing, constituting a part thereof.

Fig. 1 is a plan view of a jewelry pin showing my new design; and

Fig. 2 is a side view thereof.

I claim:

The ornamental design for a jewelry pin, substantially as shown.

MORRIS HOROVITZ.
